UNITED STATES PATENT OFFICE.

CHESTER H. BEACH, OF RACINE, WISCONSIN, ASSIGNOR TO WISCONSIN ELECTRIC COMPANY, OF RACINE, WISCONSIN, A CORPORATION OF WISCONSIN.

DRINK MIXER.

Application filed May 6, 1921. Serial No. 467,266.

To all whom it may concern:

Be it known that I, CHESTER H. BEACH, a citizen of the United States, residing at Racine, in the county of Racine and State 5 of Wisconsin, have invented certain new and useful Improvements in Drink Mixers, of which the following is a specification.

My invention relates to improvements in drink mixers such as are used at soda 10 fountains.

The object of the invention is to provide improved means for sustaining the weight of the motor and to provide a drink mixer of generally improved construction.

15 In the accompanying drawings I have illustrated one embodiment of the invention, in which—

Figure 1 is a side elevation of the device partly in section;

20 Fig. 2 is a section on the line 2—2 of Fig. 1;

Fig. 3 is a section on the line 3—3 of Fig. 1; and

25 Fig. 4 is a rear elevation of part of the device.

The structure comprises a base 1, which is preferably in the form of a casting with an upper surface of vitreous enamel to improve its appearance. A pedestal 2 is supported on said base, and is provided with a channel or groove 3 on each side, forming 30 ways or guides to guide the up and down movement of the channel-shaped member 4 which supports the motor. The lower end 35 of said channel member is provided with a pair of narrow plates 5 suitably secured thereto, as by screws 6, the inner edges of said plates sliding within the grooves 3 and serving to lock the upper and lower members 40 of the supporting structure together, in addition to guiding the upper member in its movement.

The upper end of the channel member has a small electric motor 7 secured thereto with 45 its armature shaft in vertical position, a spindle or extension 8 being secured thereto, carrying a head or agitator 9 at its lower end. Suitable conductors, encased in flexible armor 10, connect the motor with a supply 50 circuit, a switch 11 being also provided mounted in convenient position on a block of insulation 12, which is, in turn, supported on a metal bracket 13 secured to the upper end of the channel member 4. The lower

end 14 of the bracket is turned outwardly 55 and engages a resilient buffer 15 when the motor is moved to lowermost position. A plate 16 is held in position by a small bolt 17, the head of which carries the buffer 15. Said plate prevents the operator from lifting the channel member 4 so high as to disengage it from the pedestal 2.

The motor is sustained in uppermost position by means of a cord 18 secured in a slit in the lower end of the channel member and 65 passing over a pulley 19 mounted in a suitable recess in the upper front face of the pedestal. Said cord passes down through an opening in the casting and over a second pulley 20 mounted on the base 1, and then 70 passes around the periphery of a larger pulley 21. This larger pulley has a series of holes 22, into any one of which a small hook 23, on the end of the cord, may be hooked. Said pulley is mounted on a stud 75 24, with a coiled spring 25 surrounding said stud and having one end extending through an opening in said pulley and the other end projecting into an opening in the base plate 1. The spring is so tensioned as to balance 80 the weight of the motor and its associated parts, whereby the motor will remain in any position vertically to which it may be moved either up or down. The glass or other receptacle is placed within the usual 85 spring clips 26 mounted on the base.

The construction described does away with the necessity of telescoping upper and lower members, such as have been used heretofore, within which a spring has been 90 mounted to sustain the weight of the motor. In such a prior device a fairly long spring is required, whereas in the present case a small spring serves the purpose and may be so tensioned as to support the motor in any 95 desired position. The friction is such that it is not necessary to provide a locking device to hold the motor down while the agitator is stirring the liquid in the receptacle.

I claim:—

1. A drink mixer comprising a base, an upright support thereon, a motor having sliding engagement with said support, an agitator driven by said motor, and means mounted within said base for sustaining the weight of said motor.

2. A drink mixer comprising a hollow base, a pedestal thereon, a supporting mem-

ber having sliding engagement with said pedestal, a motor carried by said supporting member, an agitator driven by said motor, and a spring actuated device mounted in said base and connected with said upper member for holding said motor in different positions of vertical adjustment.

3. A drink mixer comprising a base, a pedestal thereon, a member having sliding engagement with said pedestal, a motor mounted on said member, a cord secured near the lower end of said member and extending over a support above the upper limit of movement of said end and downwardly into said base, and a member movable in a horizontal plane to which said cord is secured and impelled by a spring in a direction to counteract the weight of said motor.

4. A drink mixer comprising a base, a pedestal thereon, a member having sliding engagement with said pedestal, a motor mounted on said member, a cord secured near the lower end of said member and extending over a support above the upper limit of movement of said end and downwardly into said base, a pulley mounted on said base to turn about a vertical axis, and a coiled spring surrounding said axis and secured to said pulley, the lower end of said cord passing around said pulley and secured thereto.

5. A motor having an agitator rod depending therefrom in vertical position, a channel member to which said motor is secured, a vertical pedestal, means providing a sliding connection for said channel member on said pedestal, a hollow base supporting said pedestal, a horizontal pulley mounted within said base, a coiled spring secured to said pulley and base, and a cord extending around the rim of said pulley and passing

upwardly through said pedestal to said channel member to support the weight of said member and of said motor.

6. A drink mixer comprising a hollow base casting, a vertical stud within the same, a pulley mounted on said stud, a coiled spring surrounding said stud and secured to said base and said pulley, a pedestal mounted on said base and having a vertical recess therethrough communicating with the space in said base, a small pulley mounted beneath said recess, and a second small pulley at the upper end of said recess in said pedestal, a cord passing around said first pulley and over two smaller pulleys, a vertical member having sliding engagement with said pedestal, said cord being secured to the lower end of said member, and an electric motor secured to the upper end of said member.

7. A drink mixer comprising a motor, conductors extending therefrom, a vertical support for said motor, a switch mounted on said support and interrupting said conductors, a pedestal having channels therein, extensions on said support sliding in said channels, a spring-controlled pulley beneath said pedestal, and a cord connecting said member and pulley to balance the weight of the motor and its associated parts.

8. The combination with a drink mixer comprising a motor having a depending agitator and a supporting base, of means in said base for sustaining said motor, comprising a pulley having openings near its groove and a flexible member lying in said groove with a hook at its end caught in one of said openings and maintained under tension by the weight of said motor.

In testimony whereof, I have subscribed my name.

CHESTER H. BEACH.
